UNITED STATES PATENT OFFICE.

JULIUS KOCSIS, OF SHORT HILLS, NEW JERSEY.

SAFETY ENVELOPE.

Application filed March 17, 1923. Serial No. 625,822.

This invention relates to safety envelopes and has for its main object to provide an envelope in which money, checks or other valuable papers may be enclosed with perfect safety and sealed in a secure way against unauthorized opening of the same.

Another object of this invention is to provide an envelope of the character described, which may have comparatively large blank spaces and fields in an open position before it is sealed, said fields being adapted to receive writing and carry the letter or other notes and messages desired to be mailed in said envelope.

Still further objects will be apparent and partly pointed out as the specification will proceed.

The invention consists in the combinations and arrangements of parts hereinafter described and claimed.

The invention will be best understood by reference to the accompanying drawings forming a part of this specification, and in which:

Figure 1 is a developed plan view of one modification of my invention;

Figure 2 shows the same form of my safety envelope in a closed position;

Figure 3 is a developed plan view of another modification of my invention, while

Figures 4 and 5 show the rear and front sides, respectively, of said second modification of my safety envelope, as it would appear in a fully closed and sealed position.

Referring more closely to the drawings, the first embodiment of my invention, as shown in developed form in Figure 1, is composed of one integral piece of paper or other similar materials and has a central field 6, a lower field 7, two side fields 8 and 9, an upper flap 10 and a side flap 11, of a peculiar shape. The message to be carried in the envelope may be written on the fields 6, 7, 8 and 9, said fields being divided by the creases 12 and 13.

After the message is written, the fields 7 and 9 are folded over the fields 6 and 8, whereupon the fields 8 and 9 together are folded down over the fields 6 and 7; the four fields now occupying a rectangular space identical to that of field 6 and having said field as a base. The envelope is sealed by folding the flap 10 over the combined four fields and pasting the edges of the same on the outside of the top field by glue, paste or other suitable means as is usually done with envelopes. To have a double security, the

flap 11 is now folded over the whole combination and pasted partly on top of flap 10 and partly on top of the upper field 8. I also may fold and paste the flap 11 first on the top field 8 and fold and paste flap 10 thereafter, reversing the order of the flaps 10 and 11. The rear side of this modification of my safety envelope would appear after being sealed as shown in Figure 2, while the front of it would look like the envelopes used at present.

Another embodiment of my safety envelope is shown, in an extended developed form, in Figure 3. The main body of this envelope is composed of three fields 14, 15 and 16, adapted to carry the message or the text of the letter. After having written said message or letter and having placed the money, checks or other valuables to be mailed in my envelope, the lower field 16 is folded on the middle field 15 alongside of the crease 17. Thereupon the two rectangular side flaps 18 and 19 are folded down on this combination and pasted on top of the field 16, the whole now forming a pocket. Field 14 with its double flaps 20 and 21 and its top flap 22 is now folded down on this pocket on the line of crease 23 and the flap 22 folded over the reverse side of field 15 and pasted thereon. The two side flaps 20 and 21 are now pasted on top of both flap 22 and field 15, while their extensions 24 and 25 are further folded on the lines of crease 26 and 27, onto the front side of the envelope, that is on the outside of field 14, making an additional safety device against an unauthorized opening of my safety envelope. The rear side of the second modification of my envelope would appear, after being sealed, as shown in Figure 4, while the front side of it would look as indicated in Figure 5. The postage stamp may thereupon be pasted over and across side extension 24, while the name and address of the sender may be written across the other side flap 25. The name of the addressee can be written in the center of field 14 in the usual manner.

The several advantages of my safety envelope are obvious from the drawings and descriptions presented. My envelope is secured and sealed by several independent means so that their unauthorized opening is made almost impossible and if done, it can always be detected thereafter. The body of the envelope itself may easily serve for car-

2
rying the messages or the text of the letter, while my envelope forms a strong secure pocket for any of the valuables mentioned which it is desired to be forwarded in said envelope. Upon receipt of the envelope, the addressee may cut the flaps of the same off alongside of their creases and the whole envelope can be opened up into the form of a letter paper, with the greatest ease and facility. The edges of the flaps may also be made of an undulating or scalloping line, as at 28, thereby making the forcible opening of the same more difficult, since the edges of the flaps will be easily torn in the valleys 15 of said undulating line.

I have used these safety envelopes of mine for mailing valuables to Europe and while said valuables very often have been taken from ordinary envelopes so that the addressee could not notice the unauthorized opening of them, no valuables have ever been stolen since I have been using my new safety envelopes.

Having thus described my invention what 25 I claim as new and want to protect by Letters Patent is:

In a safety envelope having a main body formed and creased to comprise three fields of equal size and shape, and rectangular 30 end pasting flaps on the central one of said fields, a top pasting flap on the upper field having a centrally and outwardly widening contour with an undulating edge, two side pasting flaps of upwardly widening triangular shape and two top extension pasting 35

flaps on said side pasting flaps in the shape of inwardly widening triangles, their outside edges continuing and completing the outside lines of said top and side flaps into one irregular design, but said top side pasting flaps being separated from said central top pasting flap by slits, said various flaps being separated from the body of the envelope and said top side flaps from said side pasting flaps by appropriate creases, so that when said envelope is formed by folding the three fields together and pasting the end flaps thereon in the manner described and shown, said central top pasting flap may be folded and pasted on the back of 50 the same in a downwardly curved line edge across about the center of the same, said side pasting flaps may be folded and pasted over the back of the envelope, and the top pasting flap thereon, their edges providing 55 inwardly inclined undulating lines across them starting from the lower corners of the envelope to the top edge of the same, and said top side pasting flaps may be folded over and around the top edge of the envelope at the mentioned places and pasted over the front side of the envelope at the respective corners forming outwardly inclined undulating lines thereacross by their edges.

In testimony whereof, I have signed my name to this specification this 15th day of March, 1923.

JULIUS KOCSIS.
